(57) **CLAIM**

The ornamental design for a solar powered lamp, as shown and described.

DESCRIPTION

FIG. 1 is a front elevation view of the solar powered lamp showing only the lamp portion of my new design, the support being omitted for illustrative purposes only;

FIG. 2 is a top plan view thereof;

FIG. 3 is a bottom plan view of the solar powered lamp showing my new design;

FIG. 4 is a perspective view of the solar powered lamp showing only the lamp portion of my new design, the support being omitted for illustrative purposes only; and,

FIG. 5 is another perspective view of the solar powered lamp showing my new design.

1 Claim, 5 Drawing Sheets
